ECONOMIZER FOR USE WITH FURNACES

Filed Aug. 16, 1928

UNITED STATES PATENT OFFICE

JOSEPH G. STROCK, OF PITTSBURGH, PENNSYLVANIA

ECONOMIZER FOR USE WITH FURNACES

Application filed August 16, 1928. Serial No. 300,109.

This invention relates to economizers for use with furnaces and more particularly to an improvement of the economizer shown in my co-pending application, Serial No. 263,864, filed March 22, 1928, for economizers for use in conjunction with furnaces.

An important object of the present invention is to so improve the structure of the water tube element of the economizer as to avoid the necessity for employing loose baffles or applied baffles thereto.

A further and more specific object of the invention is to provide radiation or water tube sections for use in such structures having ribs which, when a plurality of the sections are combined, unite to form a baffle for directing the heating gases of the economizer downwardly about the lower portions of the sections.

20 These and other objects I attain by the construction shown in the accompanying drawings, wherein for the purpose of illustration is shown a preferred embodiment of my invention and wherein:

25 Figure 1 is a vertical sectional view through an economizer constructed in accordance with my invention;

Figure 2 is a sectional view taken on a plane extending vertically and centrally through the upper portion of the economizer, the plane of the section being indicated by the line 2—2 of Figure 3.

Figure 3 is a section on the line 3—3 of Figure 2, and

35 Figure 4 is a perspective view on a reduced scale of one of the sections of the radiator.

Referring now more particularly to the drawing, the numeral 10 generally designates a substantially rectangular casing, opposed walls of which are provided with an inlet 11 and an outlet 12. The casing is preferably supported from adjustable legs 13 permitting ready alignment thereof with a flue pipe, conducting furnace gases from the furnace to the chimney. The walls of the casing are provided with wash and extension openings 14 having removable plugs 15 permitting access to the interior of the casing.

50 Disposed within this casing is a radiator

or water tube unit of peculiar construction. This unit comprises a plurality of sections 16, each having a plurality of vertical columns 17 which connect upper and lower headers 18. Each of the upper and lower headers has in its opposite side faces bossed nipple openings 19 of the type usually provided in the ordinary sectional columnar radiator. These nipples, as well known to those familiar with the art, project outwardly from the side faces of the radiator for a short distance. The radiator has connected thereto pipes 16^a and 16^b, the pipe 16^b serving to convey water to the radiator and the pipe 16^a serving to convey water from the radiator.

In accordance with my invention, I provide the radiator with columns, preferably of an unequal number, and form upon opposite side faces of the radiator sections ribs 20 aligning with the nipple openings of the upper header and projecting outwardly from the outer faces of the section a distance equal to the depth of the bosses. This rib extends over the top of the upper header, as indicated at 21, and extends downwardly for approximately one-half of the length of the section at each face of the radiator.

It will be obvious that when the sections 16 are secured together in the usual manner, adjacent faces of the ribs of adjacent sections will come into engagement with one another, so that these ribs combine to produce, between the sections, baffle walls, which extend approximately for one-half of the length of the sections.

The ribs of the outer faces of the outermost sections extend for engagement with the walls of the casing to seal thereagainst, and the ribs upon the upper ends of the headers combine to form a baffle above the radiator which engages the top wall of the casing and effects a seal therewith. This baffle, in the applied position of the radiator, lies directly between the inlet and outlet, so that gases entering the inlet must pass downwardly therebeneath as they move to the outlet.

Since the construction hereinbefore set forth is capable of a certain range of change and modification without materially departing from the spirit of the invention, I do not

limit myself to such specific structure except as hereinafter claimed.

I claim:—

- 5 1. In an economizer, a casing, a sectional radiator within the casing, each section of the radiator having upon its side faces and at its upper end a rib structure, the rib structures of the sections combining in the assembled relation of the sections to form baffles between adjacent sections of the radiator, the ribs at the upper ends of the sections engaging the upper wall of the casing, the ribs of the outer faces of the outermost sections engaging opposite end walls thereof.
- 10 15 2. In an economizer, a casing, a sectional radiator therein, the sections of the radiator having centrally disposed means at the upper ends thereof which form baffles and which combine in the assembled relation of the sections to divide the space between the sections and to divide the space between the sections and the upper wall and upper portions of the side walls of the casing.
- 20 25 3. In an economizer, a casing, a sectional radiator therein, the sections of the radiator having centrally disposed means at the upper ends thereof which form baffles and which combine in the assembled relation of the sections to divide the space between the sections and to divide the space between the sections and the upper wall and upper portions of the side walls of the casing, the casing having an inlet and an outlet aligning with the upper portion of the radiator.
- 30 35 25 In testimony whereof I hereunto affix my signature.

JOSEPH G. STROCK.
